UNITED STATES PATENT OFFICE

2,269,276

CARBURETOR

Johan Lichtenstein, Levallois-Perret, France, assignor to Societe Generale des Carburateurs Zenith, Geneva, Switzerland, a corporation of Switzerland

Original application February 5, 1936, Serial No. 62,499. Divided and this application January 5, 1940, Serial No. 312,614. In Belgium February 8, 1935.

3 Claims. (Cl. 261—69)

I have applied for patent in: Belgium, February 8, 1935, now issued as Belgian Patent No. 407,771; Germany, application for patent of addition filed on February 8, 1936; Great Britain, February 10, 1936, now issued as British Patent of Addition 474,975; France, February 7, 1936, now issued as French Patent 804,028; Italy, February 3, 1936, now issued as Italian Patent 339,760; Poland, application for patent of addition filed on February 5, 1936; and Czechoslovakia, application for patent of addition filed on February 4, 1936.

This invention relates to improvements in carburetors for internal combustion motors, of the type described in Belgian Patent 406,646, of December 5, 1934, in the name of Societe Generale des Carburateurs Zenith, for "improvements in carburetors." The present application is a divisional of my copending application Serial Number 62,499, filed February 5, 1936.

In said Belgian patent, there is described a carburetor comprising a mixture passage having an air inlet and a mixture outlet connected to the motor, a throttle controlling the effective cross section of said passage, and a fuel outlet discharging into said passage posterior to the throttle. The carburetor is characterized essentially by a movable control member which controls the pressure at which liquid fuel is supplied to the fuel nozzle, the position of said control member being a function of the absolute pressure obtaining in the mixing chamber of the carburetor posterior to the throttle and preferably of the absolute pressure which obtains in said mixture passage in the vicinity of the fuel nozzle. This control member will be referred to hereinafter as the "manometric control member" to facilitate the description. In the preferred embodiment, a second regulating device influencing the discharge of fuel delivered by the fuel nozzle is controlled by the throttle. The manometric control member is arranged in such manner as to provide automatic functioning of the carburetor; that is to say, in such manner that the carburetor will deliver to the motor a mixture of the correct composition under all conditions of operation, and, when applied to an aircraft carburetor, is furthermore arranged in such manner as to provide an altimetric correction, that is to say in such manner as to modify the discharge of fuel in the degree required by variations in altitude.

It is known that the composition of the combustible mixture supplied to an internal combustion engine need not be an absolutely fixed one, 55

but that this composition may on the contrary vary within certain limits. As a general rule, if the richness of the mixture is increased, the motor is enabled to develop greater power, but the specific consumption is higher in such case. It is of advantage, chiefly in aviation carburetors, to provide means for modifying the richness of the mixture delivered, so as either to get maximum engine power or to diminish the specific consumption. In general, this modification of the richness is made at the will of the pilot.

The present invention has for its object an arrangement permitting the richness of the combustible mixture to be varied in carburetors of the type described in said Belgian patent.

According to the present invention, the influence of the manometric control member on the discharge of fuel may be varied by a supplemental adjusting member. This adjusting member will generally be manually controlled, but it will obviously be possible to control it automatically the same as other organs of the carburetor.

The description which follows, taken in connection with the appended drawings, will give, by way of example, a ready understanding of several ways of realizing the invention.

Figures 1, 2 and 3 are diagrammatic views of several forms of the invention;

Figures 4 and 5 are charts illustrating the operation of the embodiments shown in Figures 1 to 3.

The carburetor shown in Figure 1 comprises a mixture passage 1 having an air inlet 2 and a mixture outlet 3 connected to the motor. The effective cross section of the mixture passage 1 is controlled by a throttle 4 actuated by means of lever 5 and rod 6.

The fuel nozzle 7 discharges into the venturi 8 posterior to the throttle 4. The cross section of the fuel jet is controlled by a tapered needle 25 the shank 26 of which passes through a bushing 27 carried by the body of the carburetor. Needle 25—26 is controlled by the throttle 4 through the intermediary of the arm 28 of lever 5, line 29 and lever 30 turning about the axis 31.

The fuel nozzle 7 is supplied with liquid fuel by a pressure regulator designated as a whole by the numeral 9. The pressure regulator 9 includes a fuel chamber 10 supplied with fuel under pressure through the conduit 11 and the orifice 14. The fuel chamber 10 is closed by a flexible membrane 12 connected to a movable valve member 13 controlling the inflow of fuel

to the fuel chamber 10 through the orifice 14, the arrangement being such that any increase in pressure within the fuel chamber 10 or any decrease in pressure within the adjoining chamber 15 tends to move membrane 12 upwardly and close the valve 13, 14.

The membrane 12 separates the fuel chamber 10 from a depression chamber 15, which communicates with the air inlet 2 located at the entrance of the carburetor through a calibrated orifice 16 and a conduit 17. Orifice 16 could equally well be open directly to the atmosphere. Chamber 15 communicates also with a chamber 18 through a calibrated orifice 19. Chamber 18 communicates freely with the venturi 8 through a conduit 20. The conduit 20 opens into the venturi 8 at 21 in the vicinity of the fuel nozzle 7, that is to say at a point in the venturi where the pressure is approximately the same as at the fuel nozzle 7. The pressure which obtains in the chamber 18 is therefore approximately the same as the pressure which obtains at the fuel nozzle 7. In the chamber 18 is disposed a closed manometric bellows 22 of the aneroid capsule type, the length of which varies in accordance with the pressure obtaining in the chamber 18, to which it is exposed. The capsule 22 is fixed to the end of chamber 18 and controls only the movement of the tapered valve member 23 which controls the cross section of the orifice 19 in the same manner as in Figure 1 of the Belgian patent referred to above. Chamber 18 is connected to the chamber 15 not only through the orifice 19, but also by a bypass 145 which has a calibrated orifice 148. The bypass 145 is controlled by a manual valve 146 actuated through lever 147. The valve 146 constitutes the supplemental adjusting member.

When the manual valve is closed, the functioning of the apparatus is identical with the functioning of the apparatus shown in Figure 1 of the Belgian patent, and the richness of the mixture is represented by the curve shown in full lines in Figure 4. When the valve 146 is open, the cross section of the calibrated orifice 148 is added to the cross section of the orifice 19, and the depression transmitted to the chamber 15 is higher. Therefore the mixture delivered to the carburetor is leaner. The richness of the mixture is then shown by the curve in broken lines in Figure 4.

In the arrangement shown in Figure 2, instead of the bypass connecting the chamber 18 to the chamber 15, a bypass 149 is provided connecting the conduit 17 to the chamber 15. The bypass includes a calibrated orifice 152 and is controlled by a manual valve 150 actuated by a lever 151.

When the valve 150 is open (normal operation), the chamber 15 communicates with the air inlet of the carburetor through the calibrated orifices 16 and 152 the cross sections of which are added to each other, and it communicates with the venturi 8 of the carburetor through the orifice 19 the section of which is controlled by the tapered valve member 23. The richness of the mixture is then represented by the curve shown in full lines in Figure 5, which is similar to the curve in full lines in Figure 4. If the valve 150 is closed, the chamber 15 communicates with the air entrance of the carburetor only through the orifice 16. The depression transmitted to this chamber is then higher, and the mixture delivered by the carburetor is leaner. The leaning out thus obtained depends upon the depression of the air feed of the carburetor (the atmospheric pres-

sure). On the ground, the variation in the richness of the mixture as a function of the opening of the throttle is represented by the curve A in dotted lines in Figure 5, whereas for a given altitude, the variation in the richness of the mixture is represented by the curve B. It may be seen that the leaning out of the mixture created by the closing of valve 150 is greater the higher the altitude. Furthermore, the leaning out both on the ground and at altitude is greater the more nearly the throttle is closed.

The curves shown in Figures 4 and 5 illustrate clearly the differences in function between the apparatus shown in Figures 1 and 2 respectively. Whereas in the apparatus shown in Figure 1, the adjustment of the supplemental adjusting member modified the richness of the mixture in approximately constant proportion, whatever the opening of the throttle and whatever the altitude may be, the adjustment of the supplemental adjusting member in the arrangement shown in Figure 2 modifies the richness of the mixture in a proportion which depends at the same time on the opening of the throttle and upon the altitude.

In Figure 3 is shown an arrangement by which may be obtained results intermediate between the results obtained in the apparatus shown in Figure 1 and the apparatus shown in Figure 2. In the arrangement shown in Figure 3, the chamber 18 is connected to the chamber 15 simultaneously through the orifice 19 and the bypass 145 controlled by the valve 146 the same as the arrangement shown in Figure 1, and the conduit 17 is connected to chamber 15 simultaneously by the calibrated orifice 16 and the bypass 149 controlled by the valve 150 the same as in the arrangement shown in Figure 2. The two levers 147 and 151, which control respectively the valves 146 and 150, are coupled by means of a link 153, so that when one of the valves is open the other one is closed. The curves which represent the richness of the mixture in accordance with the positions of the valves 146 and 150, and in accordance with the altitude, are of the same shape as the curves shown in Figure 5, but the curves A and B, which correspond to the open position of valve 146 and to the closed position of valve 150, curve A corresponding furthermore to operation on the ground whereas curve B corresponds to operation at altitude, are less inclined and approach each other more closely than in the diagram shown in Figure 5, which represents the operation of the carburetor represented in Figure 2. The curves A and B approach more closely to the curve shown in dotted lines in Figure 4 when the calibrated orifice 152 in the bypass 149 is smaller relative to the calibrated orifice 148 in the bypass 145.

Although the invention has been described with particular reference to specific embodiments thereof, it is to be understood that the invention is not limited thereto, nor otherwise except in accordance with the appended claims.

I claim:

1. A charge forming device for an internal combustion engine, including an air supply passage, a throttle therein, a fuel chamber closed by a diaphragm, means for discharging the fuel from said chamber into the passage posterior to the throttle, a suction chamber closed by said diaphragm, a valve connected to said diaphragm for controlling the inflow of fuel to said fuel chamber, a conduit connecting said suction chamber with the passage posterior to the throttle, a valve operably connected to a manometric

capsule for controlling said conduit in response to pressures derived from the air supply passage posterior to the throttle, a bypass passage around said second-mentioned valve, a valve in said bypass passage adapted to be manually controlled from a point remote from the engine, a calibrated restriction in the bypass passage for limiting the maximum effective opening of the last-named valve, and a calibrated passage connecting the suction chamber with a source of substantially atmospheric pressure.

2. In a carburetor having an induction pipe, flow restricting means in said pipe including a throttle, a fuel outlet discharging in said pipe in a region of depression created by said flow restricting means, a fuel chamber having a fuel inlet and supplying fuel to said outlet, an air chamber, means responsive to the pressures in said air and fuel chambers for variably restricting the fuel inlet, calibrated passages connecting the air chamber to said region of depression and to the induction pipe anterior to the throttle, and automatic means for controlling the relative effective areas of said calibrated passages comprising a valve controlling one of said passages and an expansible capsule responsive to pressures derived from said region of depression for actuating said valve: the combination therewith of a manually operable means for varying the relative effective areas of said calibrated passages as determined by the automatic means comprising a passage in parallel with one of said calibrated passages, a valve in said passage, said valve be-

ing manually operable under substantially all engine operating conditions from a point remote from the carburetor, and a calibrated restriction in said passage for limiting the maximum effective opening of said valve.

3. A charge forming device for an internal combustion engine, including an air supply passage, a throttle therein, a fuel chamber closed by a diaphragm, means for discharging fuel from said chamber into the passage, a suction chamber closed by a diaphragm, means responsive to the pressure in said suction chamber for controlling the pressure in the fuel chamber, and means for varying the pressure in the suction chamber comprising a suction conduit connecting said suction chamber and the air supply passage posterior to the throttle, a variable restriction in said conduit, means responsive to pressures derived from the air supply passage posterior to the throttle for controlling said variable restriction, an air conduit connecting the suction chamber with the air passage anterior to the throttle, a calibrated orifice in said air conduit, a bypass passage around said variable restriction, a second bypass passage around the calibrated orifice, and manually operable means for controlling said bypass passages, said manual means being effective to simultaneously decrease the effective cross-section of one of the bypass passages while increasing the effective cross-section of the other of said bypass passages.

JOHAN LICHTENSTEIN.
